CLAIM

I claim the ornamental design for a watchcase, as shown and described.

DESCRIPTION

FIG. 1 is a top view of the watchcase.

FIG. 2 is a bottom view of the watchcase.

FIG. 3 is a side view from the right of FIG. 1.

FIG. 4 is a side view from the left of FIG. 1.

FIG. 5 is a side view from the bottom of FIG. 1.

FIG. 6 is a side view from the top of FIG. 1; and,

FIG. 7 is a perspective of the watchcase.

The material shown in broken lines forms no part of the claimed design.
